SLIDABLE AND REVERSIBLE JAW WRENCH
ESPECIALLY DESIGNED FOR WORK ON
DIFFERENT TYPE RIFLE ACTIONS

Wynn S. Vickerman, Ellensburg, Wash.

Application April 18, 1947, Serial No. 742,408

1 Claim. (Cl. 81—175)

1

This invention relates to a wrench for use by gunsmiths and others in removing and replacing threaded gun barrels from rifle actions, the primary object of this invention being to provide a wrench which is especially, although not exclusively, suited to this use, to replace the makeshift and remodelled monkey wrenches, crescent wrenches, and various hand vises generally used for the purpose, which wrench by being readily adjustable to accommodate rifle actions of different makes and shapes, eliminates the need for several such wrenches.

Another important object of this invention is to provide a rifle action wrench of the character indicated above, which applies clamping pressure equally to opposite sides of the action, instead of mainly at one side thereof, as in the case with presently used devices, in such a way as to eliminate the possibility of slipping and marring of highly polished and/or engraved actions, and in such a way as to provide sufficient strength and rigidity in itself and in its relation to the action to eliminate "spring" when pressure by hand or by means of a blow struck on the wrench handle is applied to the wrench.

Other important objects and advantageous features of this invention will be apparent from the following description and accompanying drawing, wherein merely for purposes of illustration, a preferred embodiment is set forth in detail.

In the drawing:

Figure 1 is a side elevation;

Figure 2 is a perspective;

Figure 3 is a fragmentary side elevation showing the wrench applied to a cylindrical type rifle action, such as that of a Springfield rifle;

Figure 4 is a similar view showing the wrench adjusted and applied to a flat-sided type of rifle action, such as that of a Savage or a Winchester rifle, and

Figure 5 is a fragmentary top plan view showing application of the wrench to a rifle action.

Referring in detail to the drawing, the herein illustrated embodiment of the invention, which is subject to such modifications as fall within the hereunto appended claim, is generally designated 6 and comprises essentially an inner or lower jaw 7 provided with a straight preferably integral handle 8 formed at its opposite ends with threaded parallel bores 9 into which are adapted to be threaded the clamping studs or bolts 10, smooth portions of whose shanks are rotatably accommodated in smooth bores 11 formed at the opposite ends of the outer or upper

2

jaw 12, the bolts being provided with suitable turning heads 13.

The inner jaw 7 extends crosswise with respect to the elongated handle 8, projecting for substantially equal distances on opposite sides of the axis of the handle, and presents a plane gripping surface 14 extending at right angles to said axis.

The outer or adjustable jaw 12 is in the form of a rectangular parallel sided block of the same length and width as the jaw 7 but of slightly greater depth or height. The otherwise plane working face 15 of the outer jaw 12 is formed midway between the bolts 10 with a substantially 15 90° V-shaped notch 16, of sufficient depth and aperture to receive a cylindrical rifle action 17, as indicated in Figure 3.

For the accommodation in the notch 16 of cylindrical actions having lateral projections, such as indicated at 18 in Figure 3, present on certain Enfield and Springfield rifle actions, one angulated face 19 of the notch 16 is formed with a clearance notch 20, which terminates above the lower end or edge of the notch face 19, as indicated in Figures 1 and 2, so as not to deprive this face of the notch 16 of proper engagement with the action in the absence of projections thereon like 18.

In the case of a flat-sided rifle action 21, such as that of Winchester or Savage rifles and others, the upper or outer jaw 12 is reversed on the bolts 10, so as to present to the face 14 of the lower or inner jaw 7, the plane similar parallel face 22, as shown in Figure 4.

The within described wrench is used simply by applying the jaws to opposite sides of the rifle action, with the outer jaw 12 positioned according to the type of action, and then evenly tightening the bolts 10 until the action is tightly clamped, with wrench handle extending crosswise as indicated in Figure 5 at the desired side of the rifle action. The jaws are applied to the action just in back of the recoil shoulder 23, as indicated in Figure 5. Paper, cloth or other cushioning material may be used on the working faces of the wrench jaws, before tightening the jaws.

When so tightened, and with the rifle barrel 24 held in a suitable vise, the unscrewing of the action from the barrel may be started by one or more sharp blows applied to the outer end of the handle 8.

It will be obvious that in the construction described, the equal tightening of the bolts 10 will preclude any distortion of the rifle action by jaw pressure thereon and that the equalization of

the clamping effect on opposite sides of the action will preclude any undesirable "spring" or other stress or strain, when the wrench is struck to start or to complete the threading of the action relative to the rifle barrel.

I claim as my invention:

A rifle action wrench comprising an elongated handle having a fixed jaw on one end thereof and elongated transversely with respect to said handle and presenting a substantially plane working face, an adjustable jaw similarly elongated and presenting a substantially plane working face opposed and substantially parallel to the working face of the fixed jaw, and clamping means comprising a pair of similar clamping elements connected between the jaws at their outer ends for drawing the jaws together in substantial parallel relation, another working face of said adjustable jaw being formed with a notched portion for receiving a rounded portion of a rifle action, one side of the notch in said last named

working face being provided with a right-angular clearance notch which adapts the wrench to receive rifle actions having laterally offset projections, the adjustable jaw being reversely supportable by the clamping means, whereby either of its working faces may be presented opposite the working face of the fixed jaw.

WYNN S. VICKERMAN.
